ABSTRACT OF THE DISCLOSURE

During the continuous travel of a head 35 along a spinning frame, filled bobbins 10 are doffed upwardly successively and empty bobbins are donned onto the spindles. Other mechanisms carried by the head operate in precisely timed relation to catch each doffed bobbin (FIG. 26), transfer it laterally (FIG. 28) while maintaining the unwound thread *ab* of the doffed bobbin unbroken and under positive control during stripping of this thread upwardly off from the spindle, laying a short length of the traveler end portion of this thread around the base of the empty spindle and severing of the thread between the spindle base and the doffed bobbin as an empty bobbin is donned onto the spindle thus gripping the traveler end between the spindle base and bobbin butt.

After the severing, the unwound thread of the doffed bobbin is elevated above the nose of this bobbin and, during the lateral transfer of the bobbin, a length of this thread adjacent the doffed bobbin is tucked downwardly into the hole in the bobbin, the remaining length being cut off and discarded.

This invention relates to the automatic doffing of filled bobbins off from the spindles of a spinning frame and the replacement of empty bobbins thereon during travel of a combined doffer and donner along the frame. More particularly, the invention is concerned with the handling of the thread of each doffed bobbin for recoupling to the spindle along with the donned bobbin and also to prepare the doffed bobbin for future use.

The invention is an important part of an overall new and automatic system for reducing labor costs, increasing production, and minimizing shut-downs in the handling of filled bobbins from the time of doffing from the spinning frame until the bobbins are positioned for automatic rewinding into cones or cheeses in a winder or spooler of the Barber-Colman type.

In prior doffing practice, both manual and automatic, the thread extending through the traveler on the spinning ring around each spindle is coupled to the new empty bobbin by allowing the turns which unwind during the

2

doffing from the base bunch around the butt of the bobbin to remain spiraled upwardly along the spindle after the thread is broken, the spiral becoming wedged between the spindle and the new bobbin during donning thereof. In repeated doffings, thread and lint accumulate around the spindle or within the bobbins to such an extent as to prevent proper placement of the empty bobbins on the spindles without periodic and laborious cleaning of the spindles and bobbins.

10 A primary object of the present invention is to provide a new method of automatic doffing and donning spinning frames and in which all of the thread spiraled upwardly in the doffing is removed from each spindle and recoupled automatically to the spindle and the donned bobbin only around the base of the spindle.

15 A more detailed object is to strip the spiraled thread upwardly and off from each emptied spindle, maintain such thread unbroken between the doffed bobbin and the traveler while a portion of the thread is being laid around the base of the spindle for automatic gripping thereof between such base and the butt of the empty bobbin during donning thereof.

20 Another object is to handle the unbroken thread not only for coupling to the donned bobbin but also in locating an unwound length of the thread on the doffed bobbin in a position where it will remain fixed in later handling of the bobbin.

25 Another object is to so locate the thread by tucking a short length down into the nose of the doffed bobbin.

30 Another object is to provide a novel mechanism for catching each doffed bobbin and retaining control of the same while its unwound thread is being positioned for recoupling to the spindle and replacement bobbin and also for the tuck-in positioning.

35 Still another object is to effect the tuck-in and the recoupling to the donned bobbin while the doffed bobbin is being transferred away from the position in which the bobbin is caught as it is doffed.

40 A further object is to minimize the weight of the doffer head required to be sustained by the spinning frame by floatingly mounting the head on a wheeled truck on which a substantial and heavy portion of the driving mechanism as well as the empty bobbins are stored.

45 The invention also resides in the novel method of and structures utilized for stripping off the thread left on the spindle in the doffing and retaining the same unbroken while it is being handled and positioned before severance for the recoupling and tuck-in.

50 Other objects and advantages of the invention will become apparent from the following detailed description taken in connection with the accompanying drawings, in which

CONVENTIONAL SPINNING FRAMES AND BOBBINS

In conventional spinning, tubular bobbins 10 are telescoped over or donned onto upright rotary spindles 11 (FIGS. 1, 2, 7 and 8) journaled on and spaced along the horizontal bed rail 12 of a spinning frame 13. Present day spindles, whether frictionally coupled to the bobbin at the butt end 14 or more commonly at the nose 15 (FIG. 8), have a cylindrical base 25 which telescopes quite

closely within the butt end of the bobbin usually defined by a metal ferrule 16.

Each supply thread *s*, spun from roving, advanced downwardly through drafting rolls 18 (FIG. 2), passes first through a thread eye 19 immediately above the nose of the bobbin and then is guided to the bobbin through a traveler 21 which moves around a guide ring 22 on a ring rail 23. During the spinning using conventional Z-twist spindles, the spindle is driven clockwise as viewed in FIG. 6 by a belt 31 running around a whorl or pulley 32, while the rail is raised and lowered alternately under the control of a conventional cam 33 and associated builder mechanism 33a (FIG. 1) driven from a motor 34 to distribute the spun thread along the bobbin and shape the thread mass 28 to the desired contour. After the bobbins have been filled, the rail is lowered to a position (FIGS. 1, 2 and 7) in which the guide rings 22 are held above the bobbin butts 14 until a few and variable number of turns have been wound around the bobbin 20 to form the so-called base bunch 29, the spindle drive 25 then being interrupted. The base bunch facilitates unwinding of the thread during manual doffing of the bobbin and the spiraling of enough thread around the upwardly tapered spindle for wedging between the latter and a new empty bobbin donned onto the spindle, the supply thread thus becoming recoupled to the spindle and the donned bobbin.

THE INVENTION IN GENERAL

As in some prior automatic doffers of the traveling type, filled bobbins uniformly spaced along the spinning frame are doffed successively by mechanism carried by a head 35 (FIGS. 2, 12-14 and 22-25) which is supported on the spinning frame and moved continuously along and in front of the row of bobbins starting at the right end of the frame and progressing to the left end. The direction of advance of the head is indicated by the heavy arrows in different figures.

In contrast with prior traveling doffers, the improved doffer operates to maintain the unwound thread of the doffed bobbin unbroken between the bobbin and the drafting rolls and to retain complete control and maintain an orderly positional arrangement of each doffed bobbin and its unwound thread as the bobbin is conveyed laterally away from the doffed position, while severing the thread at the proper time, recoupling the traveler or supply end to the emptied spindle and the butt of a replacement bobbin, and effecting eventual tucking of the bobbin end of the thread into the bobbin nose 15 as shown at 26 in FIG. 9.

Generally stated, filled bobbins are doffed successively from the spindles 11, caught (FIGS. 26-28) and transferred laterally (FIGS. 15 and 29) while each unwound thread all the way back to its traveler 21 is maintained unbroken, stripped off from the spindle (FIGS. 16, 31 and 32) and before severance, is manipulated so as to wrap the traveler end portion *a* around the empty spindle (FIGS. 17-19, 34 and 35) before the donning, unwind all of the base bunch 29 off from the bobbin (FIGS. 20, 35 and 36), cut off the excess length 27 (FIGS. 21 and 40) of this thread, and tuck the remaining short length 26 (FIGS. 43 and 45) into the nose of the bobbin thus leaving each bobbin with this thread disposed in a position (FIG. 9) in which it will remain during subsequent handling of the bobbin for use in a cheese or cone winder.

The present invention contemplates doffing, donning, and manipulation of the threads of each bobbin to achieve the foregoing at the rate of about sixty bobbins per minute. Considering the movement of the doffing head 35 through one spindle pitch as one cycle (see FIGS. 54a and 54b), the thread is severed at 11° about two cycles after doffing at 12°, a new bobbin is fully donned shortly thereafter at 13°, and the bobbin end of the thread is tucked into the bobbin nose at 14° after about one cycle. The thread between the drafting rolls and each traveler is referred to herein as the supply thread *s*, while

that portion of the thread unwound from the doffed bobbin and adjacent the traveler is the traveler end *a*, the portion adjacent the doffed bobbin being *b*.

Successful attainment of the foregoing and all of the objectives of the present invention is made possible by my discovery that, after doffing a filled bobbin upwardly off from a spindle, all of the unwound thread *ab* may be stripped off from the spindle without being broken (see FIGS. 7 and 26), and the portion *a* thereof recoupled effectually to the spindle during replacement of an empty bobbin thereon by positioning a relatively short length of such thread (see FIG. 8) adjacent the traveler 21 immediately above the spindle shoulder 24 and holding the thread wrapped partially around the spindle at the time an empty bobbin is donned onto the spindle. In spite of a relatively short arc of contact with the spindle and donned bobbin, enough thread *a* becomes gripped effectually between the telescoped portions of the bobbin butt 14 and the spindle base 25 to retain the coupling and resume the spinning when rotation of the spindle is restarted. The handling of the unwound thread to effect recoupling of the traveler end *a* to the donned bobbin is also utilized in the positioning of the bobbin end *b* across the nose of the doffed bobbin, cutting off the excess length 27 to be discarded and tucking the end 26 into the bobbin.

To accomplish the foregoing, the present invention involves a novel method of handling the doffed bobbins and the unwound threads thereof including the steps of locating the travelers 21 in proper positions (FIGS. 10 and 11) preparatory to doffing, catching each bobbin as it is doffed (FIGS. 26 and 28), transferring the same sidewise (FIG. 29) to provide an unwound length of thread *b* between the bobbin and the upper end 30 of the spindle (FIGS. 15 and 31), engaging such thread and drawing the same upwardly above the top of the spindle to strip all of the thread off from the spindle and form it into an inverted loop between the bobbin 10 and the traveler 21, as shown by the dotted line in FIG. 31, transferring the longer or traveler leg *a* of the loop first inwardly past and over the top 30 and behind the spindle (FIGS. 16 and 31) then reversely (FIGS. 17 and 32) relative to the direction of doffer advance, and finally forwardly and across the trailing side of the spindle (FIGS. 18 and 36) so as to utilize the advance of the doffer head 35 in wrapping a part of the thread *a* around the outer side of the spindle shoulder 24 (FIGS. 18 and 36). The partial loop thus formed becomes held effectually between the shoulder 24 of the spindle and the butt 14 of the replacement bobbin during the final seating of this bobbin (FIGS. 8, 40 and 52).

The various functions are performed by mechanisms mounted on the doffing head or frame 35 (FIGS. 1 to 6) which is supported for upright floating relative to a carriage 37 having wheels 38 which rest on and ride along the floor in front of the spinning frame as the doffer and donner advance along the latter. A power driven pinion 39 (FIGS. 3, 4 and 6) on the head meshes with the teeth of a rack bar 40 secured to the bed-rail 12 of the spinning frame and is constructed to synchronize the advance of the head precisely with the pitch of the spindles along the frame. When the spindle pitch is, for example, 3.5 inches, the pinion may be formed with fourteen teeth of .25 of an inch pitch. By changing pinions and making other adjustments, spinning frames with spindles of different spacing may be accommodated.

ALTERATION OF STANDARD SPINNING FRAME

Use of the improved doffer requires only minor changes in the construction of a conventional spinning frame. Among these is the addition of the rack bar 40 secured to the front of and extending along the full length of the bed-rail 12 for proper meshing with the power driven pinion 39 on the doffer head 35. The thread eyes 19 are disposed above the respective spindles and are on levers 42 individually swingable about a common axis 43. For

this purpose, each lever is formed beyond the eye with an extension 44 adapted to be raised (FIG. 11) and lowered (FIG. 44) at proper times in the doffing cycle by cams 45 and 46 fixed to and spaced along the moving doffing head.

Suitable means such as a notch 47 (FIG. 4) fixed to the bed-rail 12 is adapted for precise alinement with a part 48 on the doffer head 35 to enable the latter to be located along the spinning frame in a precise position relative to the spindle supporting the first bobbin to be doffed and therefore with all of the other bobbins and spindles along the frame.

PREPARATION OF BOBBIN BASE BUNCH

To enable each doffed bobbin with its thread end 26 tucked into nose hole to be later used in an automatic winder, it is important that, as an incident to the doffing and the tuck-in, all of the thread of the base bunch 29 be unwound and be led off the mass 28 at a point far enough upwardly along the mass to insure proper unwinding in response to upward pulling of the tucked-in end. Accordingly, the winding of the bunch in the final part of the spinning is controlled so that the bunch 29 is approximately of predetermined length and quite uniform in all of the doffed bobbins. This may be accomplished by timing the duration of operation of the drive of the spindles after the ring rail 23 has been lowered. For this purpose, a suitable time delay unit (not shown) is arranged to control the energization of a magnetic friction brake 49 (FIG. 1) and deenergization of the spindle drive motor 34 after lowering the ring rail in preparation for doffing. By proper adjustment of the bunch winding interval, a desired and sufficiently uniform number of turns and length of thread will be wound in the bunches of all of the bobbins of the frame.

COUPLING OF DOFFER TO SPINNING FRAME

The doffer head 35 is mounted on the trailing end of the wheeled carriage 37 for vertical adjustment under manual control to enable the drive pinion 39, after the carriage has been brought alongside the frame with the head 35 and located by alinement of the projection 48 and the notch 47 (FIG. 4), to mesh with the rack 40 and thus couple the doffer to the spinning frame preparatory to starting the doffing operation. Herein, this mounting includes two pairs of horizontal rollers 51 (FIGS. 4, 5 and 6) journaled on and spaced along the doffer head 35 and straddling an upright flange 52 on the bed-rail 12 at the front of the conventional spinning frame 13. The overhanging weight of the floating doffing head is sustained through the medium of rollers 53 on an arm 54 rigid with and depending from the head 35, the rollers bearing against the flange 52.

As shown in FIGS. 1 and 5, the doffing head 35 is guided for vertical sliding by a roller 55 riding in a slot 56 in an upright part on the carriage 37 and also by a ball joint 57 fixed to the head at 58 and slideable along an upright rod 59 fixed to the carriage. Some tilting of the head relative to the carriage is permitted by the clearance between a rod 60 fixed to and depending from the head into a ring 61 on the carriage.

Preferably, raising and lowering of the doffer head relative to the wheeled carriage is effected by selective energization of a reversible electric motor 62 (FIGS. 4 and 5) mounted on the carriage with its shaft coupled through suitable gearing to an upright screw 63 journaled on the carriage and mating with a nut 64 fixed to this carriage. The head, thus guided for vertical movement is supported by abutment with the upper end of the screw. When the carriage is positioned adjacent and in front of the bed-rail 12 with the pinion 39 disposed above the rack 40, the screw and the head may, by rotation of the motor in one direction, be lowered into mesh with the pinion thus coupling the doffer positively to the spinning frame for movement along this frame in precise relation to the spacing of the spindles 11.

DOFFER AND CAMSHAFT DRIVE AND TIMING

The pinion 39 above described is fast on the outer end of a shaft 65 (FIGS. 3, 4 and 6) disposed normal to the spinning frame and journaled in bearings 66 spaced across the doffing head 35. The shaft is driven by an electric motor 67 fixed on the trailing end portion of the wheeled carriage 37 and coupled through a belt 68 and gearing 69 (FIG. 3), a vertical shaft 70 on the carriage and a sliding spline coupling 71 (FIGS. 3 and 4) to a main vertical drive shaft 72 journaled in bearings on the frame of the doffing head. Through gearing 73, the drive shaft is coupled to the shaft 65 which constitutes one of the two camshafts which time the actuation of the doffer and donner parts. The second and parallel camshaft 74 is coupled through gearing 75 to the first shaft which also carries an indicator dial coacting with a pointer on the head. To constitute the doffing head and carriage a self-contained mobile unit, storage batteries mounted in a compartment 76 (FIG. 1) on the head end of the carriage provide the current supply for the motors 62, 67.

The gearing is so constructed that, by operation of the motor 67 with the pinion in proper mesh with the rack 40, the doffing head will be advanced along the spinning frame, a distance precisely equal to the pitch (FIG. 6) of the spindles on the frame.

TRAVELER POSITIONING PREPARATORY TO DOFFING

To enable the unwound thread of the doffed bobbin to be wrapped around the spindle shoulder 24 (FIG. 8) and recoupled to and pinched against the spindle in donning an empty bobbin thereon, it is desirable that the traveler 21 be disposed at the time of doffing within an arc 77 (FIG. 10) around the ring 22 and preferably in a position ahead or to the left of the spindle as shown in FIG. 11. One way of utilizing the advance of the doffing head to accomplish this is disclosed and claimed in the application of Richard A. Schewe et al., Ser. No. 615,402, filed Feb. 13, 1967.

Herein such repositioning of the traveler by the advance of the head is effected by a finger 78 (FIGS. 4, 10 and 11) secured at 79 to the doffing head and projecting cantilever fashion and horizontally from the leading end of the head on the back thereof. The finger is disposed just above the level of the traveler rings and is long enough to engage each traveler that has stopped within an arc 81 (FIG. 10) and carry it forwardly with the head and clockwise around the spindle as viewed in FIG. 11 as the finger moves past the spindle. The free end of the finger passes out of engagement with the traveler when the latter reaches the position shown in FIG. 11. Preferably the finger is made of flexible material and somewhat longer than the spacing of its mounting from the spindles so as to bend and pass by the spindles. Thus, the finger will engage at its free end with a traveler disposed in the position shown in FIG. 10, and, in passing by the traveler, will shift the latter clockwise around the spindle to the position shown in FIG. 11. As a result, any traveler not left within the arc 77 will be engaged by the free end portion of the finger and moved in one direction or the other to the end of this arc. The thread extending from the thread eye 19 through the traveler and to the base bunch is sufficiently loose to avoid breakage in such repositioning of the traveler.

POSITIONING THE THREAD EYE

Each thread eye 19 is maintained in normal spinning position and in alignment with the filled bobbin during the repositioning of the traveler in one camshaft cycle as indicated at 15°. In the next cycle, the thread eye is engaged by the passing cam 45 and swung upwardly at 16° to the dotted position shown in FIG. 11 and out of alignment with the bobbin now ready for doffing which occurs in the next cycle. After four cycles later and the donning of an empty bobbin, the passing cam 46 swings

the eye downwardly as indicated at 17° to normal spinning position shown in FIG. 44.

BOBBIN DOFFING

To doff a filled bobbin from a spindle, the invention contemplates the relatively gradual application of a lifting force to the ferrule or butt end 14 of the bobbin to pry the same loose from its spindle follower by a sudden increase in the lifting force by releasing energy stored in a spring 82 (FIGS. 22 to 24) so as to effect rapid acceleration and throwing or popping of the loosened bobbin upwardly off from the spindle and into a catcher 83 (FIG. 26). The application of sudden impacts and possible damage to the spindles is thus avoided.

Both lifting forces are exerted on the butt end 14 of each bobbin through the medium of a doffing member in the form of a lug 84 (FIGS. 12-14, 22 to 25) mounted on the doffing head 35 for up and down movement and made small enough to dip into the arcuate space 85 (FIGS. 14 and 22) between the spindle base 25 and the traveler ring 22 and move across a chord of this space. Thus the lug becomes disposed below the butt end 14 of the bobbin across the full radial width or wall thickness thereof and for a substantial length of travel of the lug while disposed within the traveler ring.

In the present instance, the lug is rigid with and projects horizontally and toward the plane of the spindles from the lower end of a rigid finger 86 depending from the free end of one arm 87 of a yoke 88 having a hub 89 loose on a shaft 90 supported in spaced bearings on the head 35. The yoke projects in the direction of advance of the head and its axis, which extends transversely of the head motion, is disposed somewhat below the level of the arm 87.

The finger 86 is rigid with and inclined downwardly and toward the spinning frame from the end of a lever 91 fulcrumed intermediate its ends on an upright pivot 92 on the free end of the arm 87. The opposite end of the lever carries a roller 93 riding in a slot 94 extending along the arm. A tension spring 95, acting on the lever, urges the lifter lug 84 in the direction of movement of the doffing head and to an idle position shown in FIG. 12, and in phantom in FIG. 14, this position being limited by engagement of the roller and the abutment formed by the end of the slot. The lug projects toward the spinning frame slightly beyond the plane of the outer surfaces of the spindle bases 25 so that the inclined end 96 of the lug always comes against these bases and is cammed backwardly thereby as it passes as shown in full in FIGS. 13 and 14. Thus, in spite of variations in the positions of the spindle surfaces, the lug, in passing each spindle, projects across the full radial width of the bobbin butt so that, in the doffing, the flat top 97 of the lug engages the end butt 14 as shown in FIGS. 13 and 14.

Spaced laterally from the arm 87 is the other arm 98 of the yoke 88. A roller 99 on the latter arm is the follower of a cam 101 fast on the camshaft 65. A spring 102 urges the roller downwardly against the cam whose surface 115 controls the lowering of the lug at 18° along the line 117 as shown in FIG. 25. A surface 103 on this cam controls the lifting of the lug at 20° to apply the upward prying force to the bobbin butt (FIG. 23). The accelerating doffing force is derived from the spring 82 which is of the compression type and restressed by a cam

104 during the movement of the doffing head 35 between adjacent spindles 11. This cam is fast on the shaft 65 and acts on a follower roller 105 on the depending arm of a bell-crank 106 having a hub journaled on the same shaft 90 as the yoke 88 and having an arm 107 projecting parallel to the arm 98 and connected at its free end to the lower end of a rod 108. The latter extends upwardly through the bottom of a cup 109 whose upper end is pivoted at 110 on the head 35. The spring 82, which is much stronger than the spring 102, surrounds the rod and is compressed between the cup bottom and an abutment

111 on the upper end of the rod 108. The force resulting from release of the spring is transmitted to the lifter lug 84 through the medium of the lever 107 by way of a one-way coupling formed by abutment of a downwardly facing lug 112 on the arm 98 with a lug 113 intermediate the ends of the arm 107 (see FIG. 22).

Under the control of the cam 104 and the force of the spring 102, the lug 84 is held raised and in idle position as it approaches the next spindle and filled bobbin along the line 116 (FIG. 25). Then at 18°, the cam allows the lug to dip down along the line 117 into the space 85 (FIG. 14) within the traveler ring just after passing the near end of this space. The lug remains in its lowermost position as its inclined end 96 comes into engagement with the side of the spindle, passing just beneath the butt end 14 of the bobbin to be doffed (see FIG. 22). About this time, a short rise 103 of the cam 101 is presented to the follower 99 and starts to raise the lug as indicated at 20° to engage the bobbin and then exert a positively applied force for prying the bobbin upwardly and loose from its spindle as shown in FIG. 23 and indicated by the line 118 (FIG. 25). At this time, the spring 82 is cocked, the lugs 112 and 113 are in abutment by virtue of the correlated relation of the surfaces of the cams and the abrupt fall 114 is approaching the follower 105. When it passes, as indicated at 12°, the release force of the spring swings both of the arms 87 and 107 upwardly, rapidly accelerating the raising of the lifting lug and the bobbin to the positions shown in FIGS. 24 and 25. The loosened bobbin is thus thrown or popped outwardly and upwardly ahead of the lug and off from the spindle thus completing the doffing. It should be noted that at the time of firing the cocked spring, the lugs 112 and 113 are in full contact with each other and the lug 84 with the bobbin butt 14 so that the doffing avoids sudden impacts between the parts and merely involves the rapid acceleration of parts already in abutment.

BOBBIN CATCHER

When the butt of the bobbin thus thrown upwardly reaches a position above the upper end 30 of the spindle, the motion is arrested and the bobbin is caught and held temporarily (FIGS. 26 and 28) by the quick closing against the thread mass 28 of the jaws 121 and 122 of the catcher 83 adapted to swing bodily and horizontally to carry the bobbin sidewise and out of the way of the bobbin next to be doffed while retaining complete control of the bobbin and the thread unwound from the base bunch 29 as an incident to the doffing. At the time of doffing, the jaws 122 are spring loaded and held open by a latch 124 which is released in timed relation to the doffing and the upward movement of the doffed bobbin so that the clamp formed by the jaws is closed on the thread mass of the bobbin as the latter becomes disposed between the jaws and is stopped in this position by suitable means. In the present instance, such stopping and timing of the clamp closure is effected in response to engagement of the bobbin nose 36 with a spring cushioned and yieldable abutment 125.

While the bobbin may be guided along a laterally curved path in entering the catcher 83, it travels vertically in the present instance past the jaw 121 which herein is normally stationary and positioned for engagement with the thread mass of the bobbin intermediate the ends of the latter in the stopped position of the bobbin. This jaw is on the free end of an arm 126 projecting from a rock-shaft 127 journaled in vertically spaced extensions 128 of the doffer head. Rigid with and projecting laterally from the rockshaft are vertically spaced arms 129 supporting opposite ends of a shaft 130 on which is journaled a tube 131 of a clamp-supporting frame 132 having horizontally projecting arms 133 carrying the movable jaws 122 of the clamp. These jaws are spaced vertically for engagement with the thread mass (FIG. 26) above and below the jaw 121.

Preparatory to the doffing, the jaws 122 are held in the retracted position maintained by the latch 124 as shown in full in FIG. 28, being urged counterclockwise by torsion springs 134. The latch 124 (see FIGS. 26 to 28) is an arm fulcrumed at 135 on the head 35 and having a shoulder 136 engageable with the edge of an arm 137 rigid with and projecting radially from the upper end of the tube 131. In the set position of the latch shown in full in FIG. 27, the jaws 122 are held open by engagement of the arm 137 with latch shoulder 136. This position is maintained by a spring 138 compressed between the free end of the latch and an abutment 139 fixed to the head 35. A vertical screw 141 threaded into the latch 124 is fixed at its lower end to the yieldable abutment 125. As the abutment 125 yields under the impact of the upwardly projected bobbin, the latch is raised to the position shown in phantom in FIG. 27 thus releasing the arm 137 and allowing the clamp frame to swing counterclockwise under the force of the springs 134 to the position shown in full in FIG. 26 and in phantom in FIG. 28. The thread mass 28 is thus gripped securely so that the caught bobbin is positioned accurately both laterally and vertically.

BOBBIN CONVEYOR AND TRANSFER OF CAUGHT BOBBIN THERETO

To retain control of the caught bobbins and the unwound thread thereof for recoupling to the replacement bobbin and for the tuck-in as above described, the catcher frame 132 supporting each doffed bobbin is swung laterally out of the catching position (FIGS. 26 and 28) and the bobbin therein is deposited in and held by one of a plurality of grippers 142 (FIGS. 28 to 30) on an endless horizontal conveyor 143 (FIGS. 2, 3 and 30) on which the bobbins are supported and carried laterally and in upright positions away from the doffed position. Herein, the conveyor comprises vertically spaced endless chains 144 running around pairs of idler and drive sprockets 145 which are fixed to upright shafts 146, journaled in bearings 147 (FIG. 5) on the upper part of the floating doffer head 35. The drive shaft of the sprockets is geared at 148 (FIGS. 3 and 5) to the upright drive shaft 72 the same as the camshafts 65 and 74 and the drive pinion 39 so that the chain advance is synchronized precisely with the movement of the doffer head.

Each gripper includes an upright plate 149 (FIG. 30) supported outside of the chain through the medium of lugs 150 projecting toward the chains and each joined to the two pivot pins of one chain link. Fixed to the trailing edge of the plate and projecting outwardly is a jaw 151 positioned vertically to be straddled by the catcher jaws 122. Spaced ahead of the trailing jaw 151 is a movable jaw 152 swingable on an upright pivot 153 at the leading edge of the plate 149 and urged by a torsion spring 154 toward the fixed jaw, the motion, when the gripper pocket is empty, being limited by engagement of ears 155 with the plate as shown in FIG. 30. As each empty pocket approaches the end of the chain loop, a follower lug 156 on the plate encounters a cam 157 which, as the gripper rounds the end of the loop, swings the movable jaw 152 away from the jaw 151 thus opening the gripper (FIG. 28) ready to receive the transferred bobbin. As the lug 156 rides off from the end 158 of the cam surface, the jaw 152 is released and swung against the thread mass of the bobbin (FIG. 29), which has been transferred into the open pocket.

Swinging of the catcher frame 132 clockwise as viewed in FIG. 29 to carry the doffed bobbin thereby into a gripper of the conveyor is effected by a positive motion double cam 160 (FIGS. 5, 6 and 26) fixed on the camshaft 65 and acting on followers 161 on a bell-crank 162 fulcrumed on an elongated follower shaft 163 with an upstanding arm pivotally connected at 164 to the free end of a short arm on the lower end of a vertical rockshaft 165 journaled in the head 35. An arm 166 fast on the upper end of the rockshaft straddles a link 167 between a

collar 168 loaded by a compression spring 169 and a stop 170 fixed to the rod on the inner side of the arm. The other end of the link is pivoted to the free end of an arm 171 rigid with and projecting from the upper end of the rockshaft 127 of the catcher frame 132. The arm 137 is pivotally connected by a link 172 to the arm 171 which is joined to the end of the pull link 167.

In the camshaft revolution following doffing at 12°, the cams 160 rock the shaft 165 counterclockwise (FIG. 26) at 21° swinging the frame 132 and transferring the caught bobbin sidewise into the gripper as shown in FIG. 29, this gripper having been opened by the cam 157 at 22° and closed on the bobbin at 23° when the arm 156 rides off from the cam edge 158. In this position of the bobbin, it will be observed that the jaws 121 and 122 of the catcher are tangent to the thread mass and project in the direction of the gripper advance. As a result, the bobbin is free to be carried out of the catcher clamp as the gripper continues to advance, the doffed bobbin thus being transferred automatically to the conveyor and carried in upright position around the end and then along the exposed straight side of the loop.

When the latch 124 of the bobbin catcher 83 is tripped by the doffed bobbin, its shoulder 136 is raised above the coacting arm 137 on the tubular hub 131 of the catcher jaws allowing this arm to be swung by the springs 134 past the shoulder as shown in FIG. 26 as the clamp is closed on the doffed bobbin. In the swinging of the frame 132 at 21° by the cams 160 and the link 167, the bobbin is transferred to the conveyor, the arm 137 passing the shoulder 136 and allowing the latch to drop to its set position. Then, as the frame 132 is swung back to its catching position at 24°, the arm 137 engages the shoulder 136 to arrest the swinging of the clamp jaws 122 in their open position. There is a slight overtravel of the catcher frame which carries the fixed jaw 121 thereon to the proper position for receiving and catching the next doffed bobbin. Thus, the catcher and its latch 124 are reset automatically in the bobbin transfer and return movements of the catcher frame.

In being transferred from the doffed position (FIG. 28) into the conveyor gripper (FIG. 29), the bobbin is moved sidewise and transversely of and outwardly from the plane of the spindles 11, and the motion is so short that the unwound thread *b* between the spindle and the remainder of the base bunch 29 remains unbroken. That is to say, there is enough slack developed in the thread as an incident to the doffing to accommodate such transfer. During the transfer, the unwound thread *b* at a point just below the bobbin butt 14 is laid across the free edge 175 of a bail 176 (FIG. 31) which edge extends along the doffer head just above the level of the spindle nose and, during the continued advance of the head, holds the unwound length *b* of the thread between the bail and the transferred bobbin in a quite definite and substantially horizontal position as shown in FIG. 31. Herein, the bail is fulcrumed at 177 on the doffer head and swung by a torsion spring 178 counterclockwise as viewed in FIG. 31 against a stop 179.

STRIPPING THREAD FROM SPINDLE AFTER DOFFING

As a bobbin is doffed upwardly, several turns 180 unwound from the base bunch 29 in the doffing remain spiraled around the spindle as shown in FIGS. 26 and 31. An important feature of the present invention involves removing all of these turns from the spindle, maintaining the full length of the unwound thread *b* between the traveler 21 and the base bunch 29 of the doffed bobbin unbroken and under complete control during positioning of the traveler end portion *a* for recoupling to the spindle and a donned bobbin, and of the bobbin end portion *b* preparatory to tucking the same into the nose of the doffed bobbin. In general, the thread is stripped off from the spindle in the upward movement ahead and to the left of the spindle by a V-shaped and upwardly opening fork

181 (FIGS. 15-17 and 31-33) in the present instance, which draws the thread *b* between the traveler 21 and the doffed bobbin into the form of a downwardly opening and well defined and tensioned inverted loop 182 (FIG. 32). The traveler end portion *a* of this loop is carried first past the left or leading side of the spindle (FIG. 16) and then reversely of the doffer motion, laid around and in back of the empty spindle (FIG. 17) and then is drawn forwardly across and behind the spindle (FIG. 18) and lowered to the recoupling position (FIGS. 19, 20 and 35). At the same time, (FIGS. 40 to 43), the bobbin end portion *b* of the loop is positioned preparatory to later tucking in as the doffed bobbin is carried laterally by the conveyor.

Herein the stripper or folk 181 is on the upper end of a tube 183 preferably supported for up and down movement alongside the empty spindle by a parallelogram linkage (FIG. 31) including an actuator arm 184 pivotally connected through a yoke 185 to the lower end of the tube, a guide link 186 of the parallelogram being pivoted at 187 intermediate the ends of the tube. The link extends downwardly from the end of a bell-crank 188 fulcrumed about the vertical shaft 165 fixed to the head 35. The upper end of the actuator arm 184 is fixed to a hub 190 journaled on a stud 191 projecting laterally from the bell-crank intermediate the ends of the long arm thereof. The stripper 181 is thus adapted for up and down movement by turning of the hub 190 and also for bodily lateral movement by swinging of the bell-crank 188 about the vertical shaft 165.

Swinging of the actuator arm between the retracted and upper position shown in full and phantom in FIG. 31 is effected positively by cams 192 on the cam shaft 65 acting on common followers 193 joined by a link 194 to the hub 190 at a ball-joint 195 spaced from the stud 191. A short and right angular arm 196 of the bell-crank is joined by a link 197 to a bell-crank 198 adapted to be rocked about a fixed pivot 199 by positively acting cams 200 acting through followers 201 fulcrumed on the shaft 163 and a link 202.

At its lower end, the fork 181 communicates with a slot 203 extending longitudinally of the tube 183 in which is disposed a coiled compression spring 204 (see FIG. 33) acting between an abutment formed by the pin 187 and a plunger 206 slideable in the upper end of the tube. The spring is stressed to maintain the unwound length *b* of the thread under tension light enough to maintain the shape of the inverted loop 182 and effect the desired positioning control thereof but without danger of breaking the thread.

The cams 192 and linkage are constructed and timed to raise the stripper fork at 25° at which time the thread *b* between the doffed bobbin and the top part of the spindle is disposed generally horizontally as shown in full in FIGS. 15 and 31 and in the path of the fork. As the fork is moved upwardly and is guided by the link 186 the thread length *b*, which extends laterally from the top of the spindle to the base bunch of the doffed bobbin, is picked up in the fork and drawn upwardly, this movement being far enough as shown in phantom in FIG. 31 to strip all of the turns 180 off from the spindle. In the stripping, the thread *b* may move against the force of the spring down along the slot 203 in the stripper tube a distance determined by the length of the stripped off thread so as to maintain the thread taut but without danger of breaking the same.

The path of upward movement of the stripper at 25° to the position shown in phantom in FIGS. 31 and 32 is such as to dispose the traveler end *a* of the stripped off thread ahead and to the left of the empty spindle as shown in FIG. 16 and in phantom in FIGS. 31 and 32. About this time and as explained above, the thread is engaged by the leading end 175 of a U-shaped bail 176 which is fulcrumed at 177 on the doffing head and urged by a torsion spring 178 to a retracted position against a stop 179 as shown in FIGS. 16 and 31. The bail

projects upwardly and its free end 175 is disposed above the tip of the spindles so as to be swingable over the top of the successive spindles at 26° and be retracted at 27°.

Secured to the bail shaft is a follower 207 inclined relative to the line of travel of the doffing head for engagement by the end 185 of the link 184 as shown in FIGS. 16 and 31 when the stripper fork is in its uppermost position shown in phantom in FIG. 31. The swinging of the stripper at 28° to the right from the position shown in FIG. 16 and in phantom in FIG. 31 to that of FIGS. 17 and 32 is faster than the advance of the doffing head so that the thread is carried reversely of the head motion along the end of the bail and past the right or trailing side of the spindle. Then, when the stripper is lowered at 29°, the bail will be released by the arm end 185 and allowed to retract. This, combined with the lower of the stripper, draws the thread forwardly across the trailing side of the spindle. The bell-crank 188 is swung back at 30° to return the stripper to its normal position (FIG. 31).

As the bail is retracted and the stripper lowered away from the thread. The traveler end *a* of the stripped off thread is left wrapped clockwise as shown in FIG. 18 and by the dotted line in FIG. 34 nearly a half revolution around the back of the spindle and well below the tip thereof. Between the spindle and the remaining base bunch 29 of the doffed bobbin, the thread is free, extends upwardly as shown in full in FIG. 36 and is slack enough to allow for the advance of the doffing head and continued lateral transfer of the doffed bobbin by the conveyor. The free thread lies against a guide rod 208 (FIGS. 17, 34 and 35) which is fixed on the head 35 and inclined from a point near the trailing end of the bail downwardly to the leading end of an upwardly opening notch 209 (FIG. 35) defined by the jaws of a combined clamp and shear unit 210 later to be described.

POSITIONING STRIPPED OFF THREAD PREPARATORY TO DONNING

An important and distinguishing feature of the present invention is the location and close wrapping and holding of a part of the unwound and unbroken thread *a* around the empty spindle (FIGS. 18 and 36) above the shoulder 24 prior to final seating of a donned bobbin in the position shown in FIGS. 52 and 53. Such positioning involves tightening of the thread around the spindle without danger of breaking the same, lowering the thread to the shoulder 24, and severing the thread so as to separate the same from the doffed bobbin and free the portion *b* thereof just prior to final seating of the donned bobbin so as to avoid breaking of the thread in such seating. To these ends, the thread *ab* which, as its slack is taken up by the advance of the doffing head and the conveyor and after lengthening of the same, is lowered and laid across the notch 209 of a combined shear and clamp unit 210 (FIGS. 18 to 20 and 34 to 36) which is disposed slightly above (FIG. 8) the level of the shoulders 24 on the spindles 11 and opposite each spindle at the time of seating of a donned bobbin thereon as shown in FIGS. 52 and 53.

Lowering of the wrapped around thread along the trailing and right side of the empty spindle and down along the guide rod 208 from the dotted position (FIG. 34) into the notch 209 of the shear requires an additional length of thread which is acquired by unwinding the remainder of the base bunch 29 from the butt of the doffed bobbin then held in an upright position in the conveyor and being advanced away from the spindles both transversely and longitudinally of the spinning frame. Herein this is accomplished in two steps, first by swinging a hook 224 (FIGS. 18, 34 and 36) from the upper retracted position shown in phantom to the full line position (FIG. 34). The hook is a short laterally bent portion of the free end of an arm 25 fixed to a lever 226 which is fulcrumed at 226a on a yoke 234 fixed on the doffer head at 227, to swing the hook in a plane parallel to the

plane of the spindles but spaced outwardly therefrom adjacent the guide rod 208. The hook is lowered and raised at 32° and 33° by positively acting cams 228 on the shaft 74 and having followers 229 fulcrumed on an elongated follower shaft 230 and connected through bell-crank 231 and 232 fulcrumed at 231a and 232a, and links 233 to the lever 226 fulcrumed on the yoke 234.

The hook is moved downwardly at 32° when the thread is extending upwardly from the spindle to the doffed bobbin as shown in full in FIG. 36 and carries this part of the thread downwardly along a slot 235 between two adjacent rods 236 and 237 fixed to the doffer head at 238 and 239. These rods are inclined downwardly and transversely away from the spindles as shown in FIGS. 18 and 36. As the hook moves downwardly at 32° and approaches its lower position as shown in phantom in FIG. 36, the thread slides along the guide rod 208 and is carried past a downwardly inclined lug 240 projecting from the rod 236 and stopped short of a similar lower and downwardly inclined lug 241 by which the thread is trapped temporarily between the two lugs in the elongated slot 235 as shown in phantom in FIG. 36.

In this well defined position, the now fairly taut thread *ab* is disposed in the path of a car 242 (FIGS. 18-21 and 34-36) movable upwardly along the guide rod 237 to pass by the trapped thread and downwardly past the lower lug 241 to about the level of the shear unit 210. The car is of angular cross-section with ears 243 spaced therealong and guided by the rod 237 for movement of the car between lower and upper positions shown in full and phantom in FIG. 36.

Raising and lowering of the car at the times 34° and 35° is effected by positively acting cams 244 (FIG. 42) on the shaft 74 acting on followers 245 to rock a gear segment 247 rigid therewith and fulcrumed on the shaft 246. The segment teeth mesh with a pinion 248 which in turn drives a pulley 250 that meshes with teeth on the interior of a vertically elongated and endless belt 249 (FIGS. 6 and 41) supported by and running around pulleys 250a, journaled in the doffer head. Secured to an upright straight run of the belt that moves the car alternately up and down at 34° and 35°, is a block 251 coupled to the car through a link 252 (FIGS. 36, 41, 42). As the car moves upwardly from the phantom to the full line position (FIG. 34), an inclined side 253 engages and cams the thread, then trapped between the lugs 240 and 241 (FIG. 36), out of the way after which the thread moves in beneath a downwardly opening hook 254 on the side of the car, the upper lug maintaining the trapped position of the thread while the car passes in its upward movement. In the uppermost position of the car, the thread rests on a stop finger 255 (FIGS. 19 and 34) projecting laterally from the car below the hook 254.

As the car is moved downwardly at 35° starting with the trapped thread in the position shown in full in FIG. 34 and by the dot-dash line in FIG. 36, the thread is engaged by the car hook 254 and drawn downwardly through the intermediate position as shown by the dotted line and, as the car movement continues to the lower position, the thread is formed into an L-shaped loop as shown by the dash line in FIG. 36 and in full in FIG. 35, the hook 224 having retracted upwardly at 33° in the initial part of the downward movement of the car. Thus, the trapped part of the thread is drawn downwardly past the end of the lower lug 241 and along the guide 208 and a guide 217 (FIG. 35) and into the notch 209 of the shear unit 210. Such lengthening of the thread is permitted by the unwinding of all of the remaining turns in the base bunch 29 on the doffed bobbin. By the time that the car reaches its lower position (FIGS. 20 and 35), the shear unit will have advanced to a position nearly opposite the empty spindle. At this time, the lower leg of the L-shaped loop *ab* is disposed substantially horizontally and extends as shown in FIG. 35 off from the spindle at a point immediately above the shoulder 24 and outwardly through the notch 209 of the shear and

to the car. The thread *b* then extends upwardly to the thread mass of the bobbin at a point spaced above the butt of the bobbin, the turns of the base bunch having been removed.

To insure that the thread wrapped around the spindle will be positioned accurately around the spindle and above and against an arc of the shoulder 24 but will be relatively slack at the time of final seating of a donned bobbin at 13°, additional thread is drawn off from the bobbin before closing of the clamp and shear unit 210. This is effected by movement of a slack finger 257 (FIGS. 19, 20 and 40) which engages the supply thread *s* between the traveler and the drafting rolls 18 and moves toward the spinning frame over the top of the retracted thread eye 19. Herein this finger (FIG. 40) is disposed parallel to the head travel and projects from the end of an arm 258 fulcrumed at 259 through a bracket 260 and is joined by a link 261 to the upstanding arm of a bell-crank 262 pivoted at 262a on the doffer head 35. The other arm is connected by a link 263 to a lever 264 fulcrumed on the shaft 163 and carrying the follower 265 of a cam 266 on the shaft 65. A tension spring 267 acts on the follower lever 264 to urge the follower into contact with the cam 266.

In its retracted position shown in phantom in FIG. 40, the slack finger 257 is disposed above the level of the upstanding thread eye 19 of the spindle. At 36° and as the car continues its downward motion, the cam allows the spring 267 to rock the finger toward the spinning frame and over the top of the eye to the position shown in full. The finger engages the thread between the eye and the drafting rolls and bends it as shown in FIG. 40 to provide the desired additional length of thread between the drafting rolls and the shear after the clamp 215 is closed at 11°. The finger is retracted by the cam at 37° just prior to final seating of the donned bobbin on the spindle at 13° as will be described later.

SHEAR AND CLAMP AND ACTUATION THEREOF

This shear and clamp unit 210 above referred to includes a blade 211 (FIGS. 18 to 21, 35 and 40) projecting horizontally and in the direction of advance of the head 35 and is fixed to a part of the latter. Fast on a stud 212 projecting from a yoke 213 are shearing and clamp blades 214, 215 which straddle the fixed blade 211 and coact therewith in the swinging of the yoke clockwise from the position shown in FIG. 35 to sever the bobbin thread 27 at 216 (FIG. 21) and simultaneously grip the adjacent traveler end *a* between the blades 211 and 215. An upwardly inclined extension 217 of the blade 215 coacts with the guide 208 in leading the unbroken thread *ab* downwardly into the notch 209 in the final downward movement of the car 242 as shown in full in FIG. 35. A torsion spring 218 urges the yoke 213 and the blades 214, 215 to the open position.

A link 219 depending from the yoke 213 is coupled through linkage 220 to the follower lever 221, fulcrumed on the shaft 230, and adapted to be swung by positively acting cams 222 on the shaft 74. These cams swing the yoke at 11° to cut the thread, the cams allowing the spring 218 to swing the yoke reversely and open the clamp and shear at 31°.

About the time that the thread is laid in the notch 209 of the shear unit 210, as the car 242 reaches its lower position, the jaw 214 of the shear is moved to and past the stationary jaw 211 to sever the thread at 11° (FIGS. 40 and 47) thus freeing the bobbin end portion 27 at 216 while leaving the traveler end *a* pinched and held temporarily between the jaws of the shear as shown in FIG. 21. The thread *a* remains thus held until 31° just before seating of the donned bobbin on the spindle at 13° as described later. With the thread *a* held in the clamp, the continued advance of the head 35 will carry this thread forwardly across and in front of the spindle as shown in FIG. 21 thus increasing the angle of the wrap. This insures the desired secure coupling of the thread be-

tween the butt of the donned bobbin and the spindle base.

DONNING EMPTY BOBBINS AND COUPLING SUPPLY THREADS THERETO

Empty bobbins are stored in horizontal positions in a bin 268 (FIGS. 1 and 46) at the top of the floor supported carriage 37 of the frame and ahead of the doffing head 35, the butt ends of the bobbins facing toward the spinning frame. The bobbins gravitate down the inclined bottom 269 of the bin and are picked up one by one by successive flights 270 on the upwardly moving flat side of an endless chain conveyor 271 meshing with sprockets 272, the lower one of which is driven as shown in FIG. 3 from a shaft 273, which is driven in synchronism with the vertical shaft 72. The speed of the conveyor is such that one bobbin is carried over the top of the conveyor and discharged in each doffing cycle onto a track 274 composed of a plurality of parallel extensible rods 275 disposed side by side. The track is inclined downward rearwardly and also laterally toward the spinning frame so as to induce downward tipping of the bobbins as they roll down the track. At the end of the latter, the leading bobbin moves sidewise onto a trough 276 having a downwardly and rearwardly inclined bottom 277 and an upstanding side wall 278 which engages the leading bobbin intermediate its ends as shown in FIG. 47 and locates the bobbin in the proper transverse plane for the donning. The trough is also inclined transversely of the doffer motion so as to induce endwise sliding of the bobbin to bring the butt 14 thereof against a flap 279 of flexible material projecting cantilever fashion across the track from an upright plate 280 fixed on the head 35 and defining the back wall of a chamber 281. The latter has a front wall 282, a bottom wall 283 and an upright side which curves downwardly at 284 and merges with a vertical outer wall 285 facing the spinning frame and forming part of a tube 286 through which the bobbins are donned.

As the leading bobbin resting in the track 276 is tipped upwardly from the position shown in full in FIGS. 47 and 49, the bobbin butt is slid downwardly along the trough bottom flexing flaps 279 and 279a out of the way successively. This is effected in the clockwise swinging of an arm 287 at 38°, carrying at its free end a holder 288 of L-shaped cross-section which, in the retracted position of the arm (FIG. 47), receives the nose portion of the bobbin then abutting the stop wall 278 and the flap 279. The holder arm 287 is swung back and forth by crank 289 fast on the end of the camshaft 74 (FIGS. 6, 47 and 49) and connected through a link 290 with one arm of a bell-crank 291 fulcrumed on a stud 292 and having another arm 293 joined by a link 294 (FIGS. 47 and 49) to the free depending end of a flat crank 295 loose on a stud 296 (FIG. 48). This crank carries a pin 297 disposed in the desired plane of swinging of the arm and pivotally connected to the lower bifurcated end 298 of the arm 287 which, together with the holder thereon, is urged by torsion springs 299 toward an arcuate track 201 engageable with a roller 302 on the end of the holder arm.

Swinging of the arm 287 about the stud 296 and toward and away from the track 201 is controlled by an arcuate cam 303 fixed to the head 35 and acting on a follower 304 fulcrumed on the arm at 305 and urged clockwise (FIGS. 48 to 50) by a torsion spring 306. In the counterclockwise swinging of the holder arm 287 from the advanced position shown in dotted line in FIG. 49, the follower lever 304 rides up the incline 307 of the cam 303 thus forcing the holder 288 and the arm outwardly far enough to pass the stop wall 278 in the swinging of the arm counterclockwise back to the bobbin pick-up position shown in full in FIGS. 47, 49 and 50. When the holder reaches this position, the follower 304 drops into a recess 308 at the end of the incline 307 as shown in FIG. 50 allowing the arm and holder to swing forwardly

and receive the nose portion of the terminal bobbin then resting in the trough 276, the roller 302 coming against the track 301.

In the reverse or clockwise swinging of the holder arm at 38°, the bobbin nose then disposed in the holder (FIG. 49) is raised along the track 301, the butt end 14 of the bobbin remaining against the first flap 279 until the end 309 of the holder has engaged the bobbin nose and started to slide the bobbin endwise along the track bottom 277. Under this endwise pressure, the flap 279 is flexed to allow the bobbin butt to pass and encounter a second similar flap 279a spaced down along the track and acting in a similar way to prevent free sliding of the bobbin. Beyond this flap, the butt of the bobbin slides down along the top of an inclined plate 310 of a retainer 311 which later controls the movement of the bobbin into the donning tube 286. At its upper end, the plate 310 is hinged at 312 to the chamber wall 283 and pivotally coupled at a hinge 313 to the upright flat arm of an L-shaped bell-crank 314 joined by a pivot 315 to a link 316 connected at its lower end (FIG. 51) to the free end of a crank arm 317 (FIGS. 6, 49 and 51) on the other end of the cam-shaft 74. A tension spring 318 acting on a short arm 319 of the bell-rank urges the toggle joint 313 of the bobbin retainer 311 upwardly and outwardly at 41° to the position shown in phantom in FIG. 49.

As the holder 288 with a bobbin tip therein approaches the limit of its active stroke at 39° as shown dotted in FIG. 49, the butt of the bobbin engages and passes the joint 313 thus straightening the retainer against the force of the spring 318. This swings the bobbin against a vertical guide wall 285 as shown in phantom in FIG. 49 thus holding the bobbin frictionally preparatory to its being advanced downwardly and through the tube 286 by which the bobbin is guided onto the empty spindle when the advancing head 35 comes into vertical alinement with an empty spindle. Such guiding is effected by the wall 285 coating with parallel side walls 320, 321 and an inner wall 322 which define the donning tube and are vertical extensions of the chamber walls above described. The lower end of a leaf spring 323 (FIGS. 49 and 51) depending cantilever fashion along the wall 322 bears against the side of the bobbin and after the nose thereof has passed the joint 313, thus pressing the bobbin sidewise against the wall 285 to hold the bobbin frictionally as shown in FIG. 51.

Downward movement of the bobbin beyond the position shown in phantom in FIG. 49 is effected by a pusher 325 whose shank 326 is connected through a laterally projecting pivot 327 (FIG. 47) to the free end of an arm 328 which is swung back and forth by the crank 289 and in unison with the holder arm 287 but in the reverse direction. For this purpose, the pusher arm is fixed at 329 to a second arm 330 of the bell-crank 291 projecting from the pivot 292 in a direction opposite to the arm 293. Thus, in the clockwise and counterclockwise swinging of the bell-crank, the pusher is moved downwardly at 39° and upwardly at 38° as the holder arm is swung counterclockwise and clockwise respectively.

The downward advance of the pusher from the retracted position shown in phantom in FIG. 49 starts while the donning tube 286 is approaching vertical alinement with an empty spindle and after the bobbin has been tipped by the holder arm 287 to the dotted position (FIG. 49) and then by the hinge joint 313 to the dot-dash vertical position and held frictionally against the wall 285.

By the time that the nose of the bobbin has been pushed past the hinge 313 as shown in FIG. 51, the butt end portion of the bobbin will be engaged by the lower free end of the leaf spring 323 and urged thereby against the tube wall 285 so as to be held against dropping ahead of the pusher. The bobbin retainer 311 is retracted at 40° by the lowering of the link 316 by the crank 317 (FIG. 52), the hinge 313 thus being withdrawn from engagement with the shank of the pusher and so held until after

the pusher has passed the hinge in its reverse or upward movement at 39°. The spring 323 engages the shank of the pusher and biases the latter against the wall 285 in its up and down movements.

By the time the butt of the bobbin reaches the top of the empty spindle, the two will be in vertical alinement as determined by the guiding of the butt by the leaf spring 323 and the walls at the lower end of donning tube 286. The butt thus starts to telescope down over the spindle as shown in FIG. 51 after which the lower flat end of the pusher slides across the nose of the bobbin (FIGS. 47 and 49) as the doffer head 35 advances along the spinning frame. An opening 331 (FIGS. 52 and 53) in the lower end of the trailing wall 321 of the donning tube 286 permits the latter to move past the nose of the partially donned bobbin.

Before the upper end of the bobbin passes out of engagement with the leaf spring 323, the lower free end of a second leaf spring 332 secured to and depending from the lower end of the guide tube wall 322 engages the side of the bobbin and is bent laterally as shown in FIGS. 35, 52 and 53 and stressed to force the bobbin sidewise toward and against the spindle. Enough friction is thus developed to prevent the bobbin from dropping downwardly ahead of the pusher and a member 335 by which the final seating of the bobbin on the spindle is effected. A trailing extension 336 (see FIGS. 35 and 52) of the lower end of the spring 332 continues to hold the bobbin position in the continued advance of the head 35.

During the downward movement of the pusher by clockwise swinging of the arm 328 at 39°, the holder arm 287 is swinging counterclockwise back to pick up the next empty bobbin. In this movement, the cam 307 (FIG. 50) acting on the follower 304 rocks the arm out of the plane of the stop wall 278 as shown in phantom in FIG. 48 thus allowing the arm to pass this wall and the holder 288 to move in beneath the tip of the next bobbin in the trough 276 as shown in FIGS. 47 and 49 when the follower reaches the recess 308 as shown in full in FIGS. 48 and 50.

In the lowermost position of the pusher and by the friction holding by the spring 332, the bobbin is stopped in the position shown in FIGS. 35 and 49 with the butt 14 short of the spindle shoulder 24, the thread *a* then being wrapped around the spindle just above the shoulder as shown in FIGS. 20, 35 and 51 and explained above. At this time, the thread is held taut between the drafting rolls 18 and the clamp 215 by the action of the slack finger 257 in its advanced position (FIGS. 20 and 40).

As the head advances, the pusher 325 passes over the nose of the bobbin and the bobbin-seating member 335 (FIGS. 35 and 40) starts to pass over and immediately above this nose. Herein, this member comprises a plate 337 projecting inwardly from the upstanding arm of a bell-crank 338 fulcrumed on the head at 227 and having a horizontal trailing arm connected through a coupling 340 loaded by a spring 340a to an upright link 341 joined at its lower end to an arm 342 fast on the end of an elongated follower shaft 343 carrying the followers 344 of positively acting cams 345 on the shaft 74. Shortly before the seating member 335, in moving with the doffing head, reaches the position shown in FIG. 35, the clamp 215 is opened at 31° and the slack finger 257 is released at 37°. Immediately after the thread *a* is thus freed, the ink 342 is raised at 42° by the cams 345 and this motion is transmitted through compression spring 340a to rock the bell-crank 338 (FIG. 40) counterclockwise and lower the member 337 thus moving the donned bobbin at 13° downwardly from the stopped and partially donned position shown in phantom in FIG. 8 and in full in FIGS. 35 and 47 to the final seated position shown in full in FIGS. 8, 52 and 53. The member is later retracted at 43° preparatory to seating the bobbin donned onto the next empty spindle.

The release of the clamp 215 and the retraction of the slack finger 257 at 31° and 37° loosens the thread previ-

ously wrapped around the spindle and slightly tensioned against an arc of the spindle shoulder 24 as shown in FIG. 52. This occurs substantially simultaneously with the final seating of the bobbin at 13° and telescoping of the bobbin butt 14 down over the spindle base 25 as shown in full in FIGS. 8 and 53. The wrapped around part of the thread *a* is retained on top of the shoulder 24 while the thread cut-off end 346 just released from the clamp and the supply thread *s* between the spindle and the traveler 21 are slid downwardly along the leading side of the spindle base. Thus, a substantial portion of the thread *a* becomes gripped between the bobbin butt and the spindle base as shown in FIGS. 8, 52 and 53 and coupled effectively to the spindle and donned bobbin without danger of breakage of the thread in the final seating of the bobbin.

Shortly after seating of a donned bobbin on a spindle, the thread eye 19 thereof is swung forwardly and downwardly to normal spinning position in vertical alignment with the spindle. This is effected by a plow 46 fixed to the doffer head in a position (See FIG. 44) to engage the extensions 44 of the successive thread eyes 19 and swing the same from the phantom to the full line position.

POSITIONING BOBBIN THREAD FOR TUCK-IN

During the positioning of the unwound and stripped off thread for recoupling of the supply thread *s* between the spindle and the donned bobbin, the doffed bobbin remains supported by the conveyor 143 and its sidewise advance continues as illustrated in FIGS. 16 to 21. When the thread is severed by the shear 214 at 11° and the bobbin end *b* is thus freed (FIG. 21), the bobbin will have advanced to the position shown in FIG. 40, the thread then extending from the bobbin downwardly to the car 242 as shown by the dash line in FIGS. 36 and 40 and in full in FIG. 21 horizontally to the point 216 of cut-off at the shear.

To tuck the measured length 26 of this thread *b* into the nose of the bobbin as desired (See FIG. 9), is it necessary first to raise the part of this thread adjacent the bobbin to a level above the upper end of the bobbin and adjacent the hole in the bobbin nose. Herein, such raising of the thread is effected by an elevator 350 movable along an upright guide rod 351 (FIGS. 37-39 and 41-43) between a lower position shown in phantom in FIG. 41 and an upper position shown in FIGS. 38 and 42. Herein, the elevator takes the form of a short tube of rectangular horizontal cross-section telescoped around and guided by parallel bars 357 rigid with and upstanding from the top 353 of a waste receptacle 354 which in turn is secured to the doffer head 35. A lug 355 projecting from the elevator slides along the rod 351. Between the guide bars is a flat bar 356 disposed within the elevator tube and welded to the short wall 357 thereof thus holding the elevator against turning.

The sides of the elevator 350 are formed with upwardly opening V-shaped notches 347 whose edges merge behind the outer edges of the bars 352 with curved and upwardly opening notches 348. Near their upper ends, the edges of the bars 352 are cut away to form notches 358 facing toward the spinning frame and defined by upwardly inclined lower edges 359 spaced below downwardly inclined edges 360 that form a hook 361. These edges merge at the bottom of the notches with recesses 362 having upstanding lugs 363 at the lower ends and extensions 364 of the edges 360 projecting partially across these recesses. A vertical rod 365 (FIGS. 41 and 42) joins the elevator lug 355 and the block 251 above described so that the car and elevator move up and down in unison and in successive cycles at 34° and 35° and 46° and 47° respectively while engaging the threads *b* of successive bobbins.

The thread drawn downwardly from the bobbin by the car 242 at 35° as shown by the dotted line in FIG. 40 is disposed, as an incident to lowering of the car, in the path of a hook 366 of the free end of a curved arm 367 which

is swung from the dotted line positions along the path indicated by the arrows and to the position shown in full (FIGS. 40 and 41). The thread is thus extended horizontally and disposed in front of the bars 352 (FIG. 41) and in the path of the projecting ends of the notches 348 on the elevator 350. The arm of the thread lift hook is fixed to a shaft 368 journaled in a bearing 369 fulcrumed at 369a and carrying a crank 370 coupled by a link 371 to a bell-crank 372 which is fulcrumed on the head at 373 and linked to the followers 374 of positively acting cams 374 on the shaft 74. The cams operate at 44° and 45° to swing the arm to and from the full line position (FIG. 40), the elevator being lowered as shown in phantom while the hook is lifting the thread.

As the elevator is raised at 46° with the thread thus positioned by the hook the thread is caught as shown in full in FIGS. 37 and 41 in the notch defined by the bars 352 and the edges 347 of the elevator and drawn upwardly in front of the bars, the cut-off and free end portion 216 of the thread *b* being drawn away from the shear unit 210 and through the hook 254 of the car 242. In its upward movement, the thread is bent inwardly and slides first along the vertical edges of the bars 352 and then enters the notch 358 in these bars along the inclines 359 (FIG. 37). In the continued movement of the elevator, the thread spanning the sides of the elevator is guided by the edges 347 into the notches 358 and rides up along the edges 359 and is trapped by the latter into the recesses 362 of the bars (FIG. 38). As the elevator continues to rise, the part of the thread caught in and spanning the recesses 362 is guided by the elevator edges 347 into the notches 348 which draw the thread on opposite sides of the bars 352 upwardly and through these notches. Thus, the thread spanning the notches is formed into an upwardly opening U-shaped loop 376 (FIG. 38 and 42) as the elevator reaches its upper position. This loop hangs downwardly from the elevator notches 348 and its closed lower end 377 is held in the recesses 362.

In this upper position of the elevator, the free end portion of the thread *b* hangs downwardly from one side of the elevator as shown in FIG. 42. Due to the lateral offsetting of the bobbin and the elevator, that portion of the thread between the two is carried upwardly and into a downwardly opening notch 380 defined by stationary and movable jaws 381 and 382 (FIGS. 42 and 45) of a shear 383 mounted on the head between the elevator and the bobbin. The movable jaw is one arm of a bell-crank 384 fulcrumed at 385 and having its other arm joined by a link 386 to one arm of a bell-crank 387 fulcrumed at 388 intermediate its ends and carrying at its other end a pin 389 disposed in a slot 390 near the axis of a gear segment 391. The latter is fast on an upright rockshaft 392 pivotally coupled (see FIG. 42) through a crank 393 to one arm of a bell-crank 394 fulcrumed on the shaft 163 which constitutes a double roller follower of two positively acting cams 395 on the shaft 65. The segment 391 is rocked back and forth to cut the thread at 48° and open the shear at 49° leaving the excess length 27 trapped (FIGS. 39 and 43) in the notched 348 recesses 362 of the elevator and guide bars with opposite end portions of this waste thread overhanging the elevator as shown in FIG. 43 and thus held under control for later disposal.

TUCKING THREAD INTO BOBBIN NOSE

A predetermined length 26 of thread attached to the bobbin and held above the upper end of the bobbin at the time of the cut-off is tucked down into the nose of the bobbin as shown in FIG. 9 by mechanism which may be vacuum actuated but which is preferably operated mechanically and while the lateral transfer of the bobbin continues. For this purpose, the tuck-in is effected by a hook-shaped needle 397 (FIGS. 41 to 43 and 45) on the upper end of an elongated flexible rod 398 projected upwardly through the bobbin while the butt of the latter is centered in an upwardly opening funnel 399 as shown in

FIG. 41 through which the needle rod is raised and lowered through the full length of the bobbin during the upward and downward movement 46° and 47° of the elevator. The funnel is on the upper end of a tube 400 pivotally joined by a rod 401 to one arm of a bell-crank 402 fulcrumed on the shaft 163 and rocked by a cam 404 on the shaft 65 to raise the funnel at 50° against the butt of the traveling bobbin (FIG. 42) and retain this position while the needle is being raised and lowered through the bobbin. After the needle has been lowered and the cut-off thread drawn down into the bobbin nose, the funnel is lowered at 51°. The lower end of the funnel tube is pivotally supported by a forked end of an inclined arm 405 (FIG. 42) pivoted on the head at 403 to allow some degree of tilting of the tube for accommodating the continued travel of the bobbin by the conveyor while the butt thereof is seated in the funnel during the action of the needle.

The needle reaches its upper position above the nose of the bobbin about the time that the shear 383 is actuated at 48° with the thread inclined upwardly between the bobbin and the elevator and through the notch 380 of the shear as shown in FIG. 42. The thread is then disposed below the end portion of a pin 407 (FIGS. 42, 43 and 45) pivoted at its opposite end at 408 on the free end of a second arm 409 of the bell-crank 387 and extending through a guide 410 fixed to the head 35. From the bobbin, the loose end of the thread *b* is inclined upwardly under the pin 407 and through the shear 383 in the path of a notch 411 at the end of a looper arm 412 fulcrumed on the head at 413 and fixed to a pinion 414 meshing with teeth of the segment 391 (FIGS. 42 and 45). The segment 391 is swung counterclockwise at 52° thus swinging the looper arm clockwise from the position shown in phantom in FIG. 43 to the full line position thus picking up the thread between the shear and the pin 407 just as the shear is actuated at 48°. The loose thread extending to the bobbin is looped over the pin 407 as shown in phantom in FIG. 45 and carried around the upper end of the needle below the hook 415 thereof, the loose end 26 of the thread stopping short of the looper which thus holds the thread pending the tuck-in as shown in full in FIG. 43 and in phantom in FIG. 45.

Shortly before the downward movement of the needle is initiated at 47°, the funnel 399 is lowered at 51°. As the needle 399 starts to retract at 47° and draw the loose end portion 26 of the thread down into the bobbin, the counterclockwise motion of the gear segment 391 continues swinging the bell-crank 387 clockwise to the position shown in phantom in FIG. 45 thus retracting the pin 407 through the guide 410 to release the thread at 53° for free pulling of the same into the bobbin as the needle is drawn downwardly through the latter at 49°. The measured length 26 of the unwound bobbin thread *b* is left disposed within the hole of the bobbin as shown in FIG. 9, this length being shorter than the bobbin and determined by the spacing of the bobbin from the shear 383 at the time of the cut-off.

DISPOSAL OF WASTE THREAD

As an incident to positioning of the thread *b* for tucking into the bobbin hole, the end portion of the thread beyond the eventual point of cut-off brought under position control as above described by the coaction of the elevator 350 and the recesses 362 in the guide bars 352 in forming the loop 376 within the elevator. After the cut-off at 48° and during the lowering of the elevator at 47°, the excess or waste length of the thread *b* in the form of the loop remains trapped and held intermediate its ends in the recesses 362 of the bars and below the upstanding lugs 363 as shown in FIG. 39. The loose and sheared off end portions of the thread 27 overhang opposite sides of the elevator while the closed end 377 of the upwardly opening loop is engaged by an overlying and downwardly opening hook 416 on the bar 356 that is fixed to the elevator be-

tween the bars 352. Thus, in the continued downward movement of the elevator 350, the waste length of the thread is drawn downwardly between the bars 352 and into the waste receptacle 354. The extent of this movement is sufficient to release the waste thread from the recesses 362 and the elevator and hook 416 thereon.

I claim as my invention:

1. The method of doffing filled bobbins and donning empty bobbins during the travel of a head along a spinning frame, each filled bobbin having a base bunch adjacent the butt with the latter closely telescoped down over the spindle base beyond an upwardly facing shoulder thereon, said method including the steps of,

- (a) doffing the bobbin upwardly off from the spindle to an upright position with its butt space above the top of the spindle and a portion of the thread of said base bunch left spiraled upwardly around the spindle from the traveler thereof,
- (b) transferring said bobbin bodily and laterally away from the axis of said spindle to provide an unwound length of thread between said bobbin and the upper part of the spindle, and
- (c) engaging said unwound length between the bobbin and spindle and drawing the same upwardly far enough to strip all of the spiraled turns endwise and upwardly off from the said spindle so as to form the thread between said bobbin and said traveler into a downwardly opening loop having short and long legs respectively extending downwardly to said base bunch and said traveler while maintaining unbroken the entire length of the bobbin thread between the bobbin and the spindle traveler,
- (d) lowering said loop and laying a short length of the long leg thereof around the spindle immediately above an arc of said shoulder, and
- (e) donning an empty bobbin onto said spindle to grip the wrapped around thread length between the bobbin butt and the spindle base.

2. The method as defined in claim 1 in which the long leg of said loop at the time of final stripping from the spindle is disposed in front and along the leading side of the empty spindle.

3. The method defined in claim 2 in which the wrapping of the thread around the spindle includes passing the stripped off thread over the top of the empty spindle and toward the spinning frame, and moving such thread first behind the spindle and opposite to the advance of said head and then forwardly and downwardly across the back and trailing side of the spindle immediately above and around an arc of said shoulder.

4. The method as defined in claim 1 including the step of severing the bobbin end portion of the thread at a point near the spindle just prior to final seating of the donned bobbin thereon.

5. The method as defined in claim 4 including the step of loosening the supply thread between the spindle traveler and the associated drafting rolls substantially simultaneously with the severing of the thread.

6. The method of doffing and donning as defined in claim 4 including the telescoping of the empty bobbin down over the empty spindle to a point near but short of said spindle shoulder, and finally seating the bobbin on the spindle substantially simultaneously with the severing of the thread.

7. A method of doffing and donning bobbins during the travel of a head along a spinning frame and while preparing the donned bobbins for spinning and the doffed bobbins for automatic thread pick-up, each of the filled bobbins having a base bunch of thread of approximately a predetermined length, said method including the steps of,

- (a) doffing filled bobbins upwardly and off from successive spindles during the travel of said head along said frame while leaving the thread unwound from said base bunch spiraled upwardly around the spindle,

23

- (b) catching each doffed bobbin in upright position and transferring the same laterally,
- (c) during such transfer of each bobbin, stripping all of said spiraled thread off from the emptied spindle while maintaining unbroken the full length of unwound thread between the bobbin and the traveler of the empty spindle and laying a length of such thread around an arc of the spindle near the base thereof,
- (d) drawing said unwound thread downwardly from the bobbin to unwind the remaining turns of the base bunch thereof during the continued transfer of the bobbin while positioning said thread length partially around and immediately above the shoulder at the base of the spindle,
- (e) donning an empty bobbin onto each spindle to couple the wrapped around thread between the spindle and bobbin while substantially simultaneously severing the bobbin end of the thread,
- (f) then elevating the freed and unwound length of the bobbin thread to a position adjacent and above the bobbin nose, and
- (g) finally drawing a short length of such unwound thread into the bobbin down through said nose.

8. The method defined in claim 7 in which the lateral transfer of the upright doffed bobbin is continued during laying the bobbin end portion of the cut thread across the nose of the bobbin, cutting off all but a short length of such thread, and tucking such length downwardly into the bobbin nose.

9. The method defined in claim 8 including the step of catching and confining in a common receptacle the remnant ends of the bobbin threads cut off as an incident to the tuck-in.

10. The method of doffing filled bobbins from and donning empty bobbins onto the spindles of a spinning frame during the travel of a head along the frame in front of the spindles, said method including the steps of

- (a) doffing filled bobbins upwardly from the successive spindles,
- (b) catching the doffed bobbins and transferring the same laterally,
- (c) removing from each spindle the thread left thereon in the doffing while maintaining the bobbin thread unbroken between the bobbin and the drafting rolls of the spinning frame,
- (d) positioning the thread around the base of the empty spindle,
- (e) severing the thread adjacent the spindle and substantially simultaneously donning an empty bobbin onto the spindle to secure the traveler end of the thread between the base of the spindle and the butt of the donned bobbin,
- (f) raising the thus freed portion of the bobbin thread above and laying the same across the nose of the bobbin, and
- (g) tucking a length of such thread downwardly into the bobbin nose.

11. The method of preparing for future handling and use a filled bobbin telescoped on a spinning frame spindle and having a base bunch comprising a plurality of turns of thread wound around the bobbin adjacent the butt end thereof, said method including the steps of,

- (a) doffing the bobbin upwardly off from the spindle while leaving the turns unwound from said base bunch spiraled upwardly around the spindle,
- (b) catching the doffed bobbin,
- (c) transferring the caught bobbin laterally,
- (d) stripping said spiraled turns upwardly and off from the spindle while maintaining the thread unbroken between the bobbin and the spindle traveler,
- (e) during such transfer, drawing the unbroken thread downwardly to unwind the remaining turns of said base bunch off from the bobbin, severing the thread adjacent the emptied spindle,

24

- (f) raising the portion of the unwound thread adjacent the bobbin upwardly to a position adjacent and above the bobbin nose,
- (g) cutting off the unwound thread adjacent the bobbin to a length shorter than the bobbin, and
- (h) tucking such length of thread into the nose of the bobbin.

12. The method of doffing filled bobbins from and donning empty bobbins onto the spindles of a spinning frame during the travel of a head along the frame in front of the spindles, said method including the steps of

- (a) doffing filled bobbins upwardly from the successive spindles,
- (b) catching the doffed bobbins and transferring the same laterally,
- (c) stripping upwardly and off from each spindle the thread left thereon in the doffing while maintaining the thread unbroken between the bobbin and the drafting rolls of the spinning frame,
- (d) positioning a short length of the unbroken thread around an arc of the empty spindle near the base thereof, and
- (e) donning an empty bobbin onto the spindle while substantially simultaneously severing the bobbin end portion of the thread near the spindle.

13. The method of doffing filled bobbins from and donning empty bobbins onto the spindles of a spinning frame during the travel of a head along the frame in front of the spindles, said method including the steps of

- (a) doffing filled bobbins upwardly from the successive spindles,
- (b) catching the doffed bobbins and transferring the same laterally while holding the bobbin in upright position,
- (c) severing, at a point spaced below the bobbin, the thread unwound from the bobbin,
- (d) raising above the nose of the doffed bobbin that portion of the thread adjacent the thread mass of the doffed bobbin, and
- (e) tucking a length of the elevated thread downwardly into the nose of the bobbin.

14. In a machine for handling filled bobbins doffed from the spindles of a spinning frame, the combination of, a doffing head movable along said frame and operable to project the successive bobbins upwardly and off from their spindles, a catcher mounted on said head in alignment with the path of doffing each bobbin and including clamp jaws normally laterally spaced apart horizontally to receive each doffed bobbin between them and grip the thread mass of a doffed bobbin when the jaws are closed together, a yieldable abutment disposed in the path of each doffed bobbin, and means operating as an incident to engagement of said abutment by the nose of each doffed bobbin to close said jaws on the bobbin.

15. A doffing machine as defined in claim 14 in which said jaws are normally urged toward each other and including a latch normally and releasably holding said clamp jaws open and tripped as an incident to engagement of the bobbin nose with said abutment, and means responsive to the tripping of said latch to release said jaws and allow the same to close on the thread mass of the doffed bobbin and cause the jaws to grip and hold the doffed bobbin in upright position.

16. A bobbin doffing machine as defined in claim 15 in which said abutment is yieldable vertically and said latch is tripped under the impact of the doffed bobbin as the latter is projected upwardly.

17. In a machine for handling filled bobbins doffed from the spindles of a spinning frame, the combination of, a doffing head movable along said frame and operable to project the successive bobbins upwardly and off from their spindles, a catcher mounted on said head in alignment with the path of doffing each bobbin and including a clamp having jaws normally spaced apart laterally and horizontally to receive each doffed bobbin between

them and grip the thread mass of a doffed bobbin, and means operating in timed relation to the doffing of each bobbin from its spindle and when such bobbin becomes disposed between said jaws to close said clamp and support the bobbin.

18. A doffing machine as defined in claim 17 in which said jaws are normally urged toward each other and including means releasably holding the jaws apart to receive a bobbin between them as it is doffed upwardly.

19. A bobbin handling machine as defined in claim 17 including means supporting said catcher for swinging generally horizontally back and forth between doffing and unloading position, a horizontally movable conveyor mounted on said doffing head and having outwardly opening sets of grippers disposed at the level of the thread mass of the doffed bobbin held by said catcher, said grippers having jaws movable toward each other to grip the thread mass of a bobbin held by said catcher in said unloading position, and means driving said conveyor and swinging said catcher relative to said head in timed relation to the movement of the head to effect the transfer of successive caught bobbins to successive grippers of said conveyor.

20. A bobbin handling machine as defined in claim 19 in which the jaws of said catcher and said grippers are staggered vertically for simultaneous engagement with a bobbin in said unloading position.

21. A bobbin handling machine as defined in claim 19 in which said grippers are carried by an endless conveyor and including means responsive to the movement of the conveyor relative to said head to open each gripper as it approaches a bobbin in said unloading position and then close the gripper on such bobbin.

22. A bobbin handling machine as defined in claim 19 in which the jaws of said catcher in said unloading position face in the direction of movement of said conveyor whereby each bobbin is moved out of the catcher automatically in the movement of the gripper away from said unloading position of said catcher.

23. A machine for doffing filled bobbins from a row of spinning units spaced along the ring rail on a conventional spinning frame and each including an upright rotary spindle with a base telescoped with the bobbin and terminating in an upwardly facing shoulder spaced above the butt end of the bobbin and a ring surrounding the bobbin butt and guiding a traveler therearound, said machine having, in combination, a doffing head adapted to be mounted on and guided along said spinning frame, power actuated means for driving said head along said row of spindles, a doffing device on said head engageable with the filled bobbin on each successive spindle and doffing the same upwardly off from its spindle so as to unwind thread from the bobbin and leave the same spiraled upwardly around the spindle, means for holding the doffed bobbin in upright position above the spindle and transferring the same laterally away from the spindle axis while maintaining the bobbin thread unbroken, a member mounted on said head and movable upwardly to first engage the bobbin thread between the bobbin and said traveler and then, in its continued upward movement, to strip all of the thread off from said spindle and leave the thread between the bobbin and the traveler in the form of an inverted loop having a short leg extending downwardly to the butt of the doffed bobbin and a long leg extending downwardly to said traveler, and means on said head for actuating said doffing device, said transferring means, and said stripping member in timed relation during association with each successive spindle.

24. A traveling doffer as defined in claim 23 in which the long leg of said inverted loop is disposed ahead of the spindle.

25. A doffer as defined in claim 24 including means operating in the advance of said head after the stripping to successively lay the long leg of said loop over the top of the empty spindle, carry the thread reversely of the

head advance and behind the spindle, and finally draw the thread forwardly and outwardly to dispose the same across the back and trailing side of the spindle.

5 26. A doffer as defined in claim 25 in which the stripped off thread is engaged and led over the top of the spindle and across and behind the latter by a guide carried by said head.

10 27. A doffer as defined by claim 26 in which said guide is a bail having a guiding surface extending along the path of advance of said head and including means supporting and moving the bail to carry the stripped off thread toward the spinning frame and over the top of the spindle during the advance of the head, and means for retracting the bail after the stripped off thread has passed the empty spindle.

15 28. A doffer as defined in claim 23 in which said stripping member is the free end of an upright arm supported from its lower end on said doffing head and movable upwardly and downwardly into and out of engagement with the unwound thread of the doffed bobbin, the upward movement being along a path which leaves the thread disposed ahead of the associated spindle.

20 29. A doffer as defined in claim 28 in which said stripper arm is mounted on said head for swinging back and forth longitudinally of the path of said head.

25 30. A doffer as defined in claim 29 including means operating in timed relation to the advance of said head to successively raise said arm to its upper position, swing the arm reversely of the head advance and past the empty spindle, and lower the arm.

30 31. A doffer as defined in claim 23 in which said thread of the doffed bobbin is engaged by a part slidable on said member and biased upwardly so as to yield downwardly after the thread has been tensioned between the bobbin and the associated traveler to a predetermined degree in the upward movement of the member.

35 32. A doffer as defined in claim 31 in which the thread is guided to said slidable part by a fork mounted on and opening upwardly from said member.

40 33. A doffer as defined in claim 32 in which said member comprises a tube having an upwardly opening longitudinally extending slot communicating with said fork to receive the bobbin thread, a plunger disposed within and slidable along said tube, and a spring urging said plunger upwardly along the tube under a force which allows the plunger to move downwardly in the final upward movement of the member after the thread stripped off from the spindle has become taut in the upward movement of the member.

45 34. A doffer as defined in claim 32 in which the force biasing said part upwardly is always sufficiently low to avoid breaking the bobbin thread.

50 35. A machine for doffing filled bobbins from a row of spinning units spaced along the ring rail on a conventional spinning frame and each including an upright rotary spindle with a base telescoped with the bobbin and terminating in an upwardly facing shoulder spaced above the butt end of the bobbin, and a ring surrounding the bobbin butt and guiding a traveler therearound, said machine having, in combination,

55 (a) a doffing head adapted to be mounted on and guided along said spinning frame,

(b) power actuated means for driving said head along said row of spindles,

60 (c) a device on said head engageable with the filled bobbin on each successive spindle and doffing the same upwardly off from the spindle to an upright position while leaving the bobbin thread unbroken and a portion thereof spiraled upwardly around the spindle,

65 (d) mechanism on the doffer head engageable with the thread between the bobbin and spindle and operable during the continued movement of the head to first strip the thread upwardly off from the spindle and then lay a length of the thread behind the spindle and

around an arc on the trailing side thereof and immediately above said shoulder thereof with the bobbin end of the thread extending outwardly from the plane of said spindles, and

(e) a holder on said head spaced outwardly from said plane near the level of said spindle shoulder and having an upwardly opening recess for receiving and positioning the thread as delivered by said mechanism.

36. A doffer as defined in claim 35 in which said mechanism forms the stripped off thread into the form of an inverted loop ahead of the spindle and includes means for moving the long leg of such loop over the top of the spindle, behind the latter reversely of the head advance, and then forwardly and outwardly across the path of said holder.

37. A doffer as defined in claim 35 in which said mechanism includes means for maintaining taut the unwound thread between the doffed bobbin and the drafting rolls of the spinning frame during wrapping of the thread around the spindle and positioning thereof around and above the spindle shoulder.

38. A doffer as defined in claim 35 in which the thread stripping and positioning mechanism include a member mounted on said doffer head for movement upwardly along the leading side of the spindle and downwardly along the trailing side and also back and forth along the path of travel of said head, and means actuated near the completion of the upward stripping motion to move the member backwardly along said path and carry the stripped off thread to a position beyond the trailing side of the spindle.

39. A doffer as defined in claim 38 in which the recess in said holder is defined by blades movable relative to each other to sever the thread, and means on said doffer head operating in timed relation to the advance thereof to actuate said member and sever the thread after positioning thereof adjacent said shoulder.

40. A doffer as defined in claim 39 in which said holder includes a shear for severing the thread and a clamp for gripping the traveler end of the thread and securing the same to said doffer head during the final wrapping of the held end portion around the spindle.

41. A doffer as defined in claim 40 including donning mechanism for telescoping an empty bobbin down over the spindle and seating the butt of such bobbin on the spindle base while the thread around the spindle above said shoulder, and means for releasing said clamp just prior to the final seating of the donned bobbin on the spindle, whereby to cause the freed traveler end of the thread to be gripped between the bobbin butt and the spindle base.

42. A combined doffer and donner as defined in claim 39 in which said holder includes a clamp for gripping and holding the thread during wrapping around the outer side of the spindle and a shear for severing the thread outwardly beyond the clamp, and means operating said holder to actuate said shear and clamp and leave the thread held by the clamp, said operating means acting subsequently to release said clamp just prior to the final seating of the donned bobbin on said spindle.

43. A combined doffer and donner as defined in claim 39 in which said holder includes a clamp for gripping the wrapped around thread outwardly from said spindle and tensioning means on said doffer head engageable with the thread between said traveler and the drafting rolls of the spinning frame to tension the thread around said spindle and above said shoulder prior to final seating of the donned bobbin.

44. A combined doffer and donner as defined in claim 43 including means on said doffer head operating to release said clamp and said tensioning means just before final seating of the donned bobbin on said spindle.

45. A doffer as defined in claim 35 in which the mechanism for positioning the unbroken and stripped off

thread in said holder includes a member mounted on the doffer head and moved in timed relation to the advance thereof along an upright path between a position below and disposed outwardly and opposite said holder and an upper position for engagement with the thread adjacent the doffed bobbin after release of the thread from the stripper, and including means on the doffer head operable to lead the stripped off thread into the path of downward movement of said member, and means for guiding the thread into said holder as the member approaches its lower position.

46. A doffer as defined in claim 45 in which each filled bobbin includes a base bunch partially unwound in the doffing and said member, in moving downwardly along said path, unwinds the remainder of the base bunch endwise off from the doffed bobbin.

47. A doffer as defined in claim 46 including a second member on the doffer head engageable with the supply thread above the spindle and cooperating with said first member in the unwinding of said base bunch during downward movement of the first member to control the extent of unwinding of the bobbin thread, and means operating in timed relation to the advance of the doffer head to engage the supply thread and bend the same inwardly and toward the spinning frame.

48. A machine for donning bobbins onto the empty spindles of a row along a spinning frame, each spindle including a base adapted to telescope with the butt end of a bobbin and terminating in an upwardly facing shoulder, said machine having, in combination, a head adapted to be mounted on and guided along the front of said frame, power actuated means for driving the head along said frame, a magazine movable with said head and containing a plurality of empty bobbins, mechanism operable in timed relation to the advance of said head to withdraw bobbins successively from said magazine and transfer each bobbin sidewise, tip each bobbin into vertical alignment with one of said spindles and telescope the same downwardly onto the spindle, means frictionally engaging the side of said bobbin as it is donned onto a spindle to interrupt the downward movement thereof in a partially donned position with the butt end of the bobbin spaced above said spindle shoulder, and subsequently operating means continuing the downward movement of the bobbin past said shoulder and seating the bobbin butt on the spindle and around said base.

49. A bobbin donning machine as defined in claim 48 in which each bobbin is held frictionally in said partially donned position by a yieldable member pressed against the side of the bobbin and slidably past the latter during the continued advance of said head while maintaining the bobbin position frictionally.

50. In a machine for doffing a row of filled bobbins from a spinning frame, each having a base bunch of thread comprising a plurality of turns of thread, the combination of, a doffing head movable along said row, means on said head for doffing the successive bobbins upwardly and stripping unwound thread off from the spindle while maintaining each thread unbroken, an endless horizontal conveyor having grippers spaced along its length and each adapted to receive and hold the thread mass of a bobbin and support the bobbin with its hollow nose facing upwardly, means for driving said conveyor to present grippers thereon adjacent each bobbin as it is doffed, mechanism on said head operable in timed relation to the doffing of said bobbins and the movement of said conveyor to catch each bobbin as it is doffed, transfer the same laterally, and deposit the bobbin in a passing one of said grippers, means engageable with the thread unwound from said bunch as the bobbin is doffed and drawing the thread downwardly to unwind the remainder of the bunch turns off from the bobbin butt in the course of its transfer by the conveyor, mechanism operable on the thread thus unwound to sever

the thread and to elevate the bobbin end portion thereof to and position the same across the nose of the bobbin, and means for tucking a length of the unwound thread thus positioned into the bobbin nose.

51. A machine as defined in claim 50 including means for cutting the unwound thread adjacent the bobbin to a predetermined length prior to the tuck-in.

52. A machine as defined in claim 51 in which said tucked-in length of thread is shorter than the length of the bobbin.

53. A machine as defined in claim 50 in which tucking of the thread into the bobbin nose is effected by a hook-shaped needle on the upper end of a flexible rod projected upwardly and drawn downwardly through each bobbin moving with said conveyor and in timed relation to the advances of said doffer head.

54. A machine as defined in claim 53 including means operating while said needle projects above the bobbin nose to loop the thread around the needle for drawing downwardly into the bobbin nose.

55. A machine as defined in claim 53 including a vertical guide tube surrounding said needle rod and having a funnel at its upper end receiving the butt of a bobbin and holding the bobbin and said tube in alignment in the continued travel of the bobbin and during insertion of the needle rod therethrough.

56. Bobbin doffing apparatus having, in combination, a head movable along a spinning frame into operative association with successive spinning units thereof, each unit comprising a spindle and a filled bobbin telescoped thereon and presenting an exposed downwardly facing butt end, a lifter arm on said head projecting cantilever fashion toward said frame, means on said head pivotally supporting said arm for swinging of its free end upwardly and downwardly into and out of engagement with said butt end and also horizontally about a vertical axis into and out of the plane of said units, means on said head urging said arm about said vertical axis to a normal position for engagement of the arm end beneath the bobbins, a surface on said arm end engageable with a part of each unit passed by the arm and cammed outwardly thereby and about said vertical axis as the arm passes each bobbin, and a power actuator activated while the arm end is disposed below the butt end of each bobbin to swing the arm upwardly and doff the bobbin from its spindle.

57. A machine for doffing filled bobbins upwardly from the spindles of a spinning frame while the ring rail thereof is lowered with the bobbin butts disposed within the traveler guide rings, said machine having, in combination, a head supported by and moved along said frame in front of the successive bobbins, a doffing lug adapted for entry downwardly into the arcuate space within each traveler ring and advance along a chord of such space beneath the butt of a bobbin therein, the top of said lug being adapted for abutment with the end of said butt to apply a lifting force thereto, a support on said head mounting said lug for upright movement into and out of said space, and mechanism on said head operating said support in timed relation to the advance of the head to successively lower said lug into the near end of each of said spaces, raise the lug into engagement with the butt end of the bobbin therein, exert a lifting force through the lug to accelerate the bobbin upwardly and doff the same from its spindle and raise the lug above the traveler ring before it reaches the end of said space.

58. A bobbin doffing mechanism as defined in claim 57 in which said lug is rigid with and projects horizontally and toward the spinning frame from the free end of a finger projecting downwardly and toward the spinning frame from an arm fulcrumed on said head to swing about a horizontal axis extending transversely of the frame.

59. A bobbin doffing mechanism as defined in claim 58 in which said finger is fulcrumed on said arm to swing about an upright axis and urged toward the spinning frame

for yielding engagement of the lug with the front side of the base of each spindle below the butt of the bobbin thereon whereby to insure extension of the lug across the full radial width of said butt end when passing each spindle.

5 60. A bobbin doffing mechanism as defined in claim 59 including a cam follower on said head supporting said finger, a cam on said head rotatable in timed relation to the movement thereof to lower said lug into each successive ring and then raise the lug into abutment with said butt end to pry bobbin loose from its spindle, a spring on said head adapted when released to move said follower away from said cam to accelerate the upward movement of the bobbin and doff the same from its spindle, and a second cam rotated in synchronization with the advance of said head and controlling the stressing of said spring and the sudden release of the energy stored therein.

61. Apparatus for handling bobbins doffed from a spinning frame having, in combination, a head movable along said frame, a conveyor on said head for receiving and holding a doffed bobbin in laterally spaced upright positions and transferring the same laterally away from a doffed position with a length of unwound thread hanging downwardly from the bobbin, an elevator mounted on said head and moved up and down relative thereto and alongside a bobbin advanced to a predetermined position by said conveyor, the elevator in its upper position being disposed above the nose of the bobbin on said conveyor and the elevator having an upwardly opening notch, means operating in timed relation to the movement of said conveyor for laying said unwound thread across the top of said elevator and in said notch, and means operating in timed relation to the movement of said head to tuck a length of such thread down into the bobbin through the nose thereof.

62. Apparatus as defined in claim 61 including means on said head operable while said elevator is in raised position to sever the thread between the elevator and the bobbin and leave the loose end portion of the thread hanging on said elevator.

63. Apparatus as defined in claim 62 including a waste receptacle disposed in the path of downward movement of said elevator, and means movable downwardly with said elevator and operable to deposit said loose end portion of the thread in said receptacle.

64. Apparatus for doffing filled bobbins off from and donning empty bobbins onto the spindles of a spinning frame, each filled bobbin having a base bunch around the butt thereof, said apparatus having, in combination, a head supported on said frame and driven along the latter past the successive spindles, means on said head engaging the butt of each successive bobbin to doff the latter upwardly and off from the spindle, a horizontally movable conveyor disposed above the tops of the spindles and having grippers for receiving and holding bobbins in upright positions, means for catching each bobbin as it is doffed and transferring the same into one of said grippers while maintaining the bobbin thread unbroken, means on said head including a member movable upwardly along each empty spindle to strip the thread remaining after doffing while wrapping part of such thread around the empty spindle and drawing such thread down to the base of the spindle by unwinding the remainder of the base bunch of the bobbin, and mechanism for severing the thread adjacent said base and doffing and seating an empty bobbin on the spindle to couple the traveler end of the thread between the spindle and the butt of the empty bobbin.

65. Doffing apparatus as defined in claim 64 including mechanism on said head engageable with the end portion of the bobbin thread freed by severing of the thread and operating to raise the length of such thread adjacent the bobbin above and across the nose of the bobbin during

its continued lateral transfer, and then tuck a length of such thread down into the bobbin nose.

66. In a bobbin doffing and donning machine the combination of a wheeled carriage supported on and adapted to roll along the floor in front of a spinning frame having a horizontal rack bar secured to the frame, a head carrying a power driven pinion meshing with the rack bar and mounted on said frame for movement therewith along the spinning frame and also for vertical adjustment relative to said wheeled carriage to bring said pinion into or out of mesh with the teeth of said bar, means on said head coacting with a guide on said spinning frame to support the head thereon independently of the wheeled carriage, a magazine on said head supporting frame, a bin storing empty bobbins on said carriage, and a power driven conveyor on said carriage operable to pick up bobbins one by one out of said bin, elevate the same above and then drop the same one by one into said magazine.

67. A machine for doffing filled bobbins off from and donning empty bobbins onto the spindles spaced along the ring rail of a conventional spinning frame having a ring surrounding the butt of the bobbin on each spindle and guiding a traveler around such butt and a thread eye mounted on said frame above each spindle and individually swingable upwardly and downwardly out of and back into substantial axial alinement with the spindle axis, said machine having, in combination, a doffing head adapted to be mounted on and guided along the side of said spinning frame, power actuated means for driving said head in a continuous motion along said row of spindles, a doffing device on said head engageable with the filled bobbin on each successive spindle for doffing the same upwardly off from the spindle, a donning device carried by and spaced along said head behind said doffing device and operable in passing each empty spindle to don an empty bobbin into spinning position on such spindle, means mounted on said head and actuated automatically during the approach of said doffing device to a filled bobbin to shift the associated traveler around its ring to a position opposite the leading side of the bobbin preparatory to the upward doffing of the bobbin, means on said head engageable with each of said thread eyes and ac-

tuated in timed relation to and during the continuous advance of the head to swing each successive thread eye upwardly and out of alinement with the associated spindle after shifting of the traveler thereof and before the doffing of a bobbin therefrom and then return the thread eye into alinement with such spindle after the donning of an empty bobbin onto the same.

68. A bobbin doffing and donning machine as defined in claim 67 in which the swinging of said thread eyes into and out of alinement with the respective spindles is effected by the motion of said head along said spinning frame.

69. A bobbin doffing and donning machine as defined in claim 67 in which the swinging of said thread eyes into and out of alinement with the respective spindles is effected by cams carried by and spaced along said head and engageable with followers connected to said thread eyes.
